HAND HELD CAPTIVE BALL APPARATUS

Rudolph Heinrich Heimers, Friedrich Otoman Heimers, and Siegfried Immanuel Heimers, all of 2001 Main St., Chula Vista, Calif.

Filed Sept. 16, 1957, Ser. No. 684,187

3 Claims. (Cl. 273—95)

The present invention relates generally to game apparatus and more particularly to a hand held captive ball apparatus. This application is a continuation-in-part of our co-pending application, Serial No. 385,532, filed October 12, 1953, now matured into Patent No. 2,806,700.

The primary object of this invention is to provide a captive ball apparatus wherein a considerable length of elastic cord or the like is stored on a multiple pulley system mounted on a hand held wand or beam element, the pulleys being arranged so that a maximum length of elastic can be utilized without tangling during extension and retraction.

Another object of this invention is to provide a game apparatus in which multiple sets of pulleys of different sizes are used to enable extra layers of elastic cord to be stacked one over the other in a minimum of space.

Another object of this invention is to provide such a game apparatus in which new improved guide means is used to guide the active portions of the elastic cord at all times.

Another object of this invention is to provide a game apparatus in which an excess supply of elastic cord is stored on an improved spool contained within the apparatus and capable of being locked to facilitate threading of the extra pulleys.

Another object of this invention is to provide a game apparatus in which the pulleys are easily removable for servicing.

Another object of this invention is to provide a game apparatus which is adapted for fabrication from many different materials, so that the choice of material can be according to the dictates of availability and price considerations, the exact sizes and proportions being matters easily determined to suit particular conditions and needs.

Another object of this invention is to provide a game apparatus which is practicable and inexpensive to manufacture.

Finally, it is an object to provide a game apparatus of the aforementioned character which is simple and convenient to operate and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure, and in which:

Figure 1 is a top plan view of the apparatus;

Figure 2 is a fragmentary sectional view taken on the line 2—2 of Figure 1;

Figure 3 is an enlarged fragmentary sectional view taken on the line 3—3 of Figure 1;

Figure 4 is an enlarger sectional view taken on the line 4—4 of Figure 1; and

2

Figure 5 is an enlarged fragmentary sectional view taken on the line 5—5 of Figure 2.

Similar characters of reference indicate similar or identical elements and portions throughout the specification and throughout the views of the drawing.

Referring now to the drawing in detail, the apparatus includes a wand 10 which is an elongated beam-like member, generally I-shaped in cross section and having a flat central web 12 with spaced, parallel side rails 14. At one end, the side rails 14 extend beyond the web 12 to provide a pair of long arms 16, having longitudinal opposed grooves 18 on their inner faces and co-planar with said web.

Fitted between the arms 16 and abutting the web 12 is an inner pulley block 20 comprising a plurality of spaced, parallel plates 22 interconnected at one end by a common spacer member 24 and defining runways 25 between the plates. Extending laterally from the pulley block are lugs 26 and 28 which are a tight sliding fit in the grooves 18 and serve to center the pulley block in alignment with the web 12. The inner pulley block 20 has a transverse bore 30 in which are a plurality of freely rotatable pulleys 32 mounted on a shaft 34, said shaft being held at one end in the end plate 36 of the pulley block and having at the other end a cap 38 which seats in a socket 40 in the other end plate 42. The pulleys 32 are aligned with the runways 25 between the plates 22 and the plates each have raised restrictor knobs 44 on their confronting faces on both sides of the bore 30 and on their extended portions 46 remote from the spacer member 24. This type of pulley structure is fully described in the above mentioned co-pending application.

Also fitted between the arms 16 is an outer pulley block 50, the structural details of which are exactly analogous to those of the inner pulley block 20, except that the outer pulley block 50 is somewhat larger and contains pulleys 52 of larger diameter than the pulleys 32. This outer pulley block 50 abuts the outer end of the inner pulley block 20, so that the two constitute a double-pulley assembly. The pulley blocks 20 and 50 are easily removed or inserted by sliding them longitudinally, the lugs 26 and 28 on each block riding in the grooves 18 of arms 16 at one end of the wand and in the grooves 56 of arms 54 at the other end of the wand.

At the other end of the wand 10, the side rails 14 are extended to provide a pair of stub arms 54 having opposed grooves 56 in their inner faces similar to the grooves 18. Fitted between the stub arms 54 are a further inner pulley block 20 and an outer pulley block 50. A length 50 of elastic cord 60 is wound in adjacent loops first around the pulleys 32 and extending along both sides of the web 12 in close proximity thereto, then the elastic cord is wound around the larger pulleys 52, as shown in Figure 3, which hold this second layer of elastic cord clear of the first layer on the smaller pulleys 32. The elastic cord 60 is prevented from jumping off the pulleys by the restrictor knobs 44 since the gap between each opposed pairs of restrictor knobs is less than the width of the elastic cord. Thus it is possible to hold more than double the normal amount of elastic cord on a wand of given length and width by using sets of pulleys of different sizes at each end of the wand, the pulleys of each pulley block at each end of the wand being aligned with corresponding pulleys of the other pulley blocks but spaced longitudinally of the wand from the pulleys of the other pulley blocks.

Secured to the stub arms 54 is a roller guide head 62 having a pair of spaced, parallel socket portions 64 which fit over said stub arms, said socket portions being interconnected at their outer ends by a head block 66. The inner ends of the socket portions 64 are connected by a centering plate 68, having a pair of vertically opposed

slots 70 aligned with the longitudinal axis of the wand 10 and disposed on either side of the web 12. On the inner face of each socket portion 64 is a bearing 72 between which is mounted a freely rotatable centering roller 74 having a circumferential groove 76 in axial alignment with the slots 70. Fixed in the head block 66 is a frame 78 in which are mounted two pairs of spaced parallel rollers 80 and 82, the pairs being mounted at right angles to each other. This roller structure is also fully described in the above mentioned co-pending application.

The free end 84 of the elastic cord 60 is threaded between the rollers 80 and 82 and falls naturally into one of the slots 70 and a circumferential groove 76 of the centering roller 74, the end of the elastic cord being fixed to the ball 86 or other captive element, as shown in Figures 1 and 3. The free end 84 thus passes through the central portions of the pulley blocks 20 and 50 and the centering roller 74 holds this free end substantially clear of the loops of elastic cord to prevent binding.

The other or fixed end 88 of the elastic cord 60 is secured to a spool 90 which comprises a pair of generally flat, plate-like elements 92 and 94 having arm portions 96 and which are aligned with each other by pins 98 adjacent each end of the plate 92 and integral therewith. The spool 90 is rotatably mounted on a support rod 100, the plate element 92 having a transverse channel 102 to constitute a bearing for said rod. The support rod 100 has an extended portion 104 which extends parallel to one side of the spool 90 and has an inwardly turned end 106 which is journaled in the side of a foot block 108. This foot block 108 is fixed between a pair of socket portions 110 which fit over the ends of the arms 16, the complete unit comprising an end cap 112. The edges of the spool 90 and the extended portion 104 fit into widened portions 114 of the grooves 18, when the end cap 112 is in place, so that the spool is stored in non-rotatable position. To add or remove elastic cord on the spool 90, the end cap 112 is removed and the spool 90 pulled longitudinally from the wand 10, and the extended portion 104 of the support rod 100 is swung outwardly about the axis of end portion 106 and is shifted axially on said end portion to lock in position in a notch 116 in the foot block 108 which holds the rod in place. The end cap 112 is then replaced with the spool 90 supported clear of the wand 10 for free rotation, the extended portion 104 being recessed in the notch 116 and clear of the arm 16.

There is a special utility in the specific two-piece spool construction described above when considered in relation to the dual pulley block construction, since this special spool permits the locking thereof against rotation when in extended position. For example, when the inner pulley blocks have been loaded with elastic cord, the outer pulley blocks must be inserted and it is convenient to lock the spool against rotation to prevent further unwinding until such time as the outer blocks are in place. To effect this locking, the spool is simply shifted longitudinally on the support rod 100 until the spool is so close to the wand as to have insufficient clearance for rotation. At least one of the plates 92 and 94 is sufficiently flexible to allow the spool to be shifted off center so that the support rod is no longer in the channel 102.

The operation of this invention will be clearly comprehended from a consideration of the foregoing description of the mechanical details thereof, taken in connection with the drawing and the above recited objects. It will be obvious that all said objects are amply achieved by this invention.

It is understood that minor variation from the form of the invention disclosed herein may be made without departure from the spirit and scope of the invention.

and that the specification and drawing are to be considered as merely illustrative rather than limiting.

We claim:

1. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having a pair of parallel arms at each end thereof; said pulley blocks being slidably inserted and removably supported on and between said arms; said inner pulley blocks being retained by said outer pulley blocks against movement in one direction longitudinally of the support member; all said pulley blocks being frictionally engaged with said arms; and means removably secured to the extremities of said arms and also engaging said outer pulley blocks for further securing that the latter be held in place.
- 20 2. Apparatus according to claim 1 wherein one of the last mentioned means is a guide head including two crossed pairs of spaced, parallel rollers and a centering roller disposed between said rollers and said pulley blocks and having a circumferential groove therein; one of said pulley blocks having a substantially central runway and a pulley therein aligned with the circumferential groove of said centering roller.
- 30 3. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having parallel arms extending from each end thereof; said pulley blocks being removably secured on and between said arms; a support rod pivotally mounted to swing outwardly from said arms; a spool freely rotatably mounted on said support rod; said spool comprising two substantially coextensive plates with a bearing defined at their center portions for said support rod, at least one of said plates being sufficiently flexible to permit the spool to be shifted off center and locked against rotation by engagement with an adjacent portion of said support member, whereby the insertion of said outer pulley blocks into place during the loading or winding of the elastic cord is facilitated.
- 40 4. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having parallel arms extending from each end thereof; said pulley blocks being removably secured on and between said arms; a support rod pivotally mounted to swing outwardly from said arms; a spool freely rotatably mounted on said support rod; said spool comprising two substantially coextensive plates with a bearing defined at their center portions for said support rod, at least one of said plates being sufficiently flexible to permit the spool to be shifted off center and locked against rotation by engagement with an adjacent portion of said support member, whereby the insertion of said outer pulley blocks into place during the loading or winding of the elastic cord is facilitated.
- 50 5. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having parallel arms extending from each end thereof; said pulley blocks being removably secured on and between said arms; a support rod pivotally mounted to swing outwardly from said arms; a spool freely rotatably mounted on said support rod; said spool comprising two substantially coextensive plates with a bearing defined at their center portions for said support rod, at least one of said plates being sufficiently flexible to permit the spool to be shifted off center and locked against rotation by engagement with an adjacent portion of said support member, whereby the insertion of said outer pulley blocks into place during the loading or winding of the elastic cord is facilitated.
- 60 6. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having parallel arms extending from each end thereof; said pulley blocks being removably secured on and between said arms; a support rod pivotally mounted to swing outwardly from said arms; a spool freely rotatably mounted on said support rod; said spool comprising two substantially coextensive plates with a bearing defined at their center portions for said support rod, at least one of said plates being sufficiently flexible to permit the spool to be shifted off center and locked against rotation by engagement with an adjacent portion of said support member, whereby the insertion of said outer pulley blocks into place during the loading or winding of the elastic cord is facilitated.
- 70 7. A hand held captive ball apparatus comprising: an elongated, rigid support member; inner pulley blocks on said member and disposed on opposite sides of a central portion of the member; outer pulley blocks on said member on the remote sides of said inner pulley blocks; all said pulley blocks having pulleys and said pulleys having their axes substantially on a common plane; the pulleys of the outer pulley blocks being coplanar with and being greater in diameter than the corresponding pulleys of the inner pulley blocks; a single elastic cord wound serially in adjacent loops on the pulleys of the inner pulley blocks and also having outer loops wound serially upon the pulleys of the outer pulley blocks with the outer loops spanning the inner pulley blocks and out of contact therewith; a captive ball secured to one end of said elastic cord; and means to secure the other end of the elastic cord; said support member having parallel arms extending from each end thereof; said pulley blocks being removably secured on and between said arms; a support rod pivotally mounted to swing outwardly from said arms; a spool freely rotatably mounted on said support rod; said spool comprising two substantially coextensive plates with a bearing defined at their center portions for said support rod, at least one of said plates being sufficiently flexible to permit the spool to be shifted off center and locked against rotation by engagement with an adjacent portion of said support member, whereby the insertion of said outer pulley blocks into place during the loading or winding of the elastic cord is facilitated.
